SUPPORT BRACKET FOR RETAINING A MIRROR

Ralph E. Conner, North Wilkesboro, N.C., assignor to
The Carolina Mirror Corporation, North Wilkesboro,
N.C., a corporation of North Carolina

Filed Mar. 8, 1963, Ser. No. 73,896

Term of patent 14 years

(Cl. D33—3)

FIGURE 1 is a front perspective view of a support bracket for retaining a mirror, showing my new design.

FIGURE 2 is a vertical transverse section view of my mirror mount, taken along the line 2—2 of FIGURE 1; and

FIGURE 3 is a rear perspective view thereof.

The broken lines showing a mirror fragment in FIGURE 1 are for illustrative purposes only.

I claim:

The ornamental design for a support bracket for retaining a mirror, as shown and described.
